DISPLAY STAND

Oswald B. Carson, Scarsdale, N. Y., assignor to
 American Hard Rubber Company, New York,
 N. Y., a corporation of New York

Application February 27, 1933. Serial No. 653,704

4 Claims. (Cl. 211—58)

This invention relates to a stand or rack for holding display cards to which are attached a number of articles for successive removal from the card, and sale. The object of the invention 5 is to provide a stand or rack of this kind with means for holding or storing a plurality of these cards in groups, with one card of each group displayed outermost so that the articles on it are fully exposed for display and may be success- 10 sively removed when sold. Each rack in the display stand is provided with grooves for holding the outermost visible card, and also with a pocket behind said card for storing a number of like cards each holding merchandise. When the 15 articles displayed on the outermost display card have been removed from the card, it may be taken out of its groove and replaced by one of the filled cards held in the storage pocket behind it.

20 More specifically, the invention comprises a rotatably mounted stand or rack having a number of storage compartments in each of which cards with attached merchandise are held, each of the compartments being provided with an outer groove to receive the edges of a card similar to those held behind it, and display it and its attached merchandise. The entire rack is mounted upon an upright or standard, on which it may be rotated so that its various sides and 25 the cards presented thereon may be easily displayed to the customer for selection of the merchandise held in the rack.

In the accompanying drawing, in which the preferred embodiment of the invention is shown, 30 Fig. 1 is a vertical sectional view through the display stand, on the line 1—1 of Fig. 2, looking in the direction of the arrows, and Fig. 2 is a sectional view on the line 2—2 of Fig. 1, looking in the direction of the arrows.

40 The display stand or rack in the form of a box-like structure, is supported upon a suitable base 3 preferably made of pressed metal, and cup-shaped in cross-section to form it into a rigid member. It is provided with a central de- 45 pressed portion 4 from which rises a vertical rod or standard 5 upon which the rack is supported. The rack is provided with two spaced frames each formed of the connected strips or frame members 6, 7, 8 and 9. The strips indicated at 6 and 7 50 have their ends 10 bent at right angles and these portions 10 are secured to the faces of the strips 8 and 9 as shown in Fig. 2 so that the four united strips 6, 7, 8 and 9 are formed into a square, and reinforced by the cross braces 11 and 12.

55 The rod or standard 5 extends through the

upper and lower sets of cross braces 11 and 12, the upper set of braces resting upon the shoulder 13 of the rod 5 on which the entire rack rotates. The two square frames, each composed of the connected strips 6, 7, 8, 9, 11 and 12 are held in 60 their spaced relation by vertical strips 14 which are attached to the inner faces of the laterally bent ends 10 of the strips 6 and 7. Vertical strips 15, similar in shape to those shown at 14, are secured to the inner faces of laterally bent ends 65 16 formed on the strips 8 and 9. Additional vertical strips 17 are secured to the outer faces of the laterally bent ends 16, these strips 17 cooperating with those shown at 14 and 15 to form grooves or guideways 18 for the reception of the 70 edges of cards 19. The strips 15 and 17 have their ends bent angularly as at 20 and 21 respectively, the space 22 located between these bent ends 20 and 21 constituting a groove or guideway for the 75 reception of a single card 19, as shown at the left in Figs. 1 and 2.

The bottom frame of the rack is provided with horizontally extending flanges 23 projecting laterally from its strips 6, 7, 8 and 9 which act as shelves for the cards held in the respective 80 grooves 18 and 22 and also for additional cards placed in back of the cards so held.

When a card is held in each of the grooves 22 it cooperates with the flanges 20, the frame members 8 or 9 and the shelf 23 to form a pocket for 85 containing a stack of similar cards as shown in dotted lines in Fig. 1. Similarly, cards placed in the grooves 18 cooperate with the flanges 25 on the vertical strips 14, the frame members 6 and 7 and the shelves 23 to form like storage pockets. 90 These pockets act as storage compartments for cards to which merchandise, as for example combs 24, are attached. When the outermost card in any one of the portions of the rack and held in grooves 18 or 22, has been depleted of its 95 attached merchandise, one of the other cards contained in the storage pocket in back of the empty card, may be inserted in the outer groove 18 or 22. The improved display rack thus not only acts as a means for displaying the articles 100 of merchandise attached to the cards, but also holds a supply of filled cards, which cards may be successively placed outermost in display position in the rack when the cards on display have had their attached merchandise removed. 105

What I claim is:—

1. A display rack comprising, a card-holding frame, a support for rotatably holding the frame, said frame having a plurality of vertically disposed braces spaced from one another to define 110

card-receiving grooves between them, the braces extending between and connecting upper and lower frame elements, said frame elements having laterally projecting end portions to which the 5 vertically disposed braces are attached, and shelf portions extending from the lower frame element and situated in position to support the lower edges of cards held in the card-receiving grooves and also to support cards held between the projecting ends of the frame elements and in back 10 of the cards held in the grooves.

2. A display rack comprising, a vertically disposed rod, a frame mounted to rotate thereon, said frame having vertically disposed elements 15 spaced to provide grooves, each of which receives a card, an upper frame portion composed of several connected horizontally disposed strips having angular ends secured to the vertical elements, a similar lower frame portion having 20 lateral flanges forming shelves to support the lower ends of cards held in the grooves and also to support an additional supply of cards held between the angular ends of the upper and lower

frame members, and in back of those held in the grooves.

3. A display rack having upper and lower frames, vertical braces connecting the frames, lateral shelves on the lower frame, both frames 80 having laterally bent ends cooperating with the shelves to form card-receiving pockets, the vertical braces having longitudinal flanges cooperating with one another to form card-receiving 85 grooves at the front of the card-receiving pockets. 85

4. A display rack comprising, a card-holding frame, a support on which the frame is rotatably mounted, said frame having vertical braces formed with longitudinally-flanged edges defining single card-receiving grooves between them, upper 90 and lower frame portions connected by the vertical braces, said frame portions having projecting parts secured to the vertical braces to form the same into side walls of card-receiving pockets located behind the card-receiving grooves, 95 and flanges on the lower frame portion forming bottoms for said pockets and grooves. 95
